US00D885528S

(12) **United States Design Patent** (10) **Patent No.:** **US D885,528 S**
(45) **Date of Patent:** **** May 26, 2020**

(54) **MIST GENERATOR**

(71) **Applicant:** **Panasonic Intellectual Property Management Co., Ltd.**, Osaka-shi, Osaka (JP)

(72) **Inventors:** **Mitsunari Fujii**, Hyogo (JP); **Taiki Terada**, Shiga (JP); **Hiroyuki Tanaka**, Hyogo (JP); **Yoshikazu Tanaka**, Tokyo (JP); **Yuki Ueda**, Osaka (JP)

(73) **Assignee:** **Panasonic Intellectual Property Management Co., Ltd.**, Osaka (JP)

(**) **Term:** **15 Years**

(21) **Appl. No.:** **29/663,532**

(22) **Filed:** **Sep. 17, 2018**

(30) **Foreign Application Priority Data**

Mar. 19, 2018 (JP) 2018-005677

(57) **CLAIM**

We claim the ornamental design for a mist generator, as shown and described.

DESCRIPTION

FIG. 1 is a perspective view of a mist generator of the present invention;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged view of the section thereof taken along lines 9-9 of FIG. 2; and,

FIG. 10 is an enlarged view of the section thereof taken along lines 10-10 of FIG. 9.

The broken lines show parts of the mist generator that represent unclaimed subject matter and form no part of the claimed design.

1 Claim, 10 Drawing Sheets
